(57) **CLAIM**

The ornamental design for a watch as shown and described.

DESCRIPTION

FIG. 1 is a front, perspective view of a watch showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front view thereof in an alternate position;

FIG. 8 is a front view thereof in a second alternate position; and,

FIG. 9 is a front view thereof in a third alternate position. The broken lines depict portions of the watch that form no part of the claimed design.

The drawings include surface shading which illustrates contour and not surface ornamentation.
